UNITED STATES PATENT OFFICE

JAMES ARCHIE BELL, OF SHELBYVILLE, KENTUCKY

AUTOMOBILE SIGNAL

Application filed October 20, 1931. Serial No. 570,017.

This invention relates to the type of automobile signals which are carried by the vehicle and include an arm movable longitudinally outward from the side of the vehicle to give the proper signal to a following vehicle and inward upon the conclusion of the signal, under control of the driver of the vehicle. A primary purpose of the invention is to provide a signal of the type stated which will be of the utmost simplicity of construction, and will be operative to disclose the intentions of the driver as to whether he is about to stop or to make a right hand turn or to make a left hand turn.

This purpose is secured from the construction illustrated in the accompanying drawing and herein described and claimed. In said drawing, wherein like characters of reference indicate like parts in the several views:

Fig. 1 is a partial view of the forward part of an automobile provided with my improved signal and shows the latter in retracted position in full lines, and in the several positions to which it is adjustable in signalling the intentions of the driver, in dotted outline;

Fig. 2 is a longitudinal section on the line 2—2 of Fig. 1;

Figs. 3 and 4 are cross sections on the lines 3—3 and 4—4, respectively.

The signal constituting this invention consists of a supporting and guiding member A and an arm B slidably mounted on said member A, together with posts a and b, all relatively constructed and arranged to permit the arm to be projected and retracted with relation to the member A and when in its fully projected position to be turned about the post a so as to extend at an inclination downward or upward from its rear end according to the requirements in relation to the signal to be given. The construction and relative arrangement of the member A, arm B and posts a and b, according to this invention furthermore are such that when the arm is in partially projected position it will stand out straight from the side of the vehicle and while capable of being easily adjusted longitudinally and pivotally by the

operator will at all times be held against any annoying rattling tendency.

To these ends, the member A, hereinafter called "body member", is formed with a longitudinal slot 10 whose forward end terminates in arcuate extensions 11 and 12 respectively projecting forwardly therefrom and in an upward and downward direction with relation thereto. The post a, which is carried by the body member, occupies a horizontal position across the mouth of said member and is in alinement with the slot 10. The arm B is formed with the slot 13 in registration with the slot 10 in the body member and through which the post a extends. The post b is carried by the arm B and arranged rearward of the slot 13. In the movements of said arm outward and inward relatively to the body member A, the post b traverses the slot 10 in said body member and in the movements of the arm about the post a to a downwardly inclined position the post b traverses the slot extension 11 and in the movement of said arm about said post a to an upwardly inclined position said post b traverses the slot extension 12.

The body member A is preferably formed to completely encase the arm B throughout almost the entire length of said arm, when the latter is retracted, as shown best in Figs. 1, and it will be noticed that the arm B fits closely within said body member, with its edges in contact with the longitudinal walls and its front and rear surfaces in contact with the inner surfaces of the front and back elements, respectively, of the hollow portion of said body member. It will also be noticed that the outer end portion of said body member is expanded laterally and correspondingly hollowed to afford room in said end for the pivotal movement of the rear end of the arm when the latter is being adjusted to a downward inclination or to an upward inclination; and finally it will be noticed that the posts a and b co-operate with each other and with the walls of the hollow body member and edges of the arm in guiding the latter in its longitudinal and pivotal movements and in overcoming any undue rattling tendency.

Any suitable means for moving the arm B relatively to the body member A may be resorted to in practice. A very simple means for this purpose comprises a head 15 to be grasped by the driver of the vehicle in adjusting the arm. The head here shown is mounted upon the stem of the post b and has a threaded engagement with said stem, as shown at 16, so that it may be tightened or loosened by a slight turn.

It will be understood that in practice this signal is mounted within the vehicle in a position convenient to the driver, who by grasping the head moves the arm outward or inward relatively to the body member and pivotally upward or downward as the occasion demands. If he desires that the arm shall stand out straight from the side of the vehicle he terminates the outward movement thereof before the post b has reached the arcuate slot extensions 11, 12. If, on the other hand, the nature of the signal to be given requires that the arm extend at an upward inclination or at a downward inclination, the operator of the signal projects it to the point at which the said post b will be in position to traverse said slot extensions 11 or 12, as the case may be, and will then move the rear end of the arm within the proper extension. If he desires that it be held against displacement, he may give the head 15 a slight turn to cause it to press tightly against the body member and thereby create sufficient frictional resistance to displacement of the arm to make it practicable for the operator to release said head, so that his hands will be free to operate the vehicle. When practicable, and usually it will be practicable to do so, he may hold the arm in its adjusted position until the signal may be withdrawn, by maintaining his grasp upon the head.

It will be understood that the body member and the arm may be made of either wood or metal, whichever is preferred, and it will be noticed that the construction is of the utmost simplicity, may be readily applied to any motor vehicle and when so applied will present a neat appearance. The outer end of the arm is preferably, as shown, formed to resemble an open hand, and the forward end of the body member is shaped to conform to the shape of the hand, the major portion of which is encased in the forward end of said body member while the remainder of the arm is encased within the remaining portion of the body member, when the arm is in its retracted position. In short, the arm is entirely encased when in its retracted position within the body member except for the extreme forward end of said arm and, moreover, is fitted in said body member sufficiently tightly to avoid rattling while permitting it to have its required movements relatively to said body member.

Having thus described the invention what

I believe to be new and desire to secure by Letters Patent, is:—

1. An automobile signal including a body member and an arm slidably engaged with said body member and having a longitudinal slot extending through the sides thereof, said body member provided at its forward end with a post which extends into said slot and about which the rear end of the arm has pivotal movement when the arm has been adjusted to its outward position relatively to the body member, to thereby enable the arm to occupy an inclined position relatively to the body member.

2. An automobile signal comprising an arm having a longitudinal slot and a body member supporting said arm, said arm being slidably engaged with said body member and provided with a post rearward of its slot and said body member having in a wall thereof a slot traversed by said post in the longitudinal movement of the arm relatively to the body member and also having, forward of said slot, a post which extends through the slot in the arm and about which the arm has pivotal movement when in its outward position relatively to the body member.

3. An automobile signal according to claim 2 in which the slot in the wall of the body member terminates at its forward end in arcuate forwardly extending openings respectively extending upward and downward from the slot and the post which projects from said arm traverses said openings, respectively, in the pivotal movements of the arm.

4. An automobile signal according to claim 2 in which the body member is hollow and the major portion of the arm fits snugly therein when said arm is in its retracted position, and the posts and slots are so correlated as to co-operate with said snug fit in effectively guiding the arm in its movements and in overcoming any tendency of the arm to rattle.

5. An automobile signal according to claim 2, in which the arm has a laterally expanded outer end and the outer end of the body member is correspondingly expanded, and in which also the slot in the wall of said body member extends into the laterally expanded end of said member and terminates within said end in arcuate forwardly extending openings respectively extending upward and downward from the slot in a substantially concentric relation with the post which extends from said body member, and the post which projects from the arm traverses said openings, respectively, in the pivoted movements of the arm.

6. An automobile signal comprising a body member and an arm slidably engaged with said body member, said arm having a longitudinal slot which extends through the sides thereof and said body member having

at its forward end a post which extends into said slot and about which the rear end of the arm may be turned pivotally in either upward or downward direction when the arm 5 has been moved to its outward limit relatively to the body member, said body member and arm having means cooperating to hold the arm in a horizontal position when the arm has been projected from the body 10 member but has not yet reached the position at which it may be turned pivotally.

7. An automobile signal comprising a body member and an arm slidably engaged with said body member, said body member and 15 arm having registering longitudinal slots, a post carried by the rear end of the arm and traversing the slot in the body member, a second post carried by the body member and extending through the slot in the arm, said 20 second post being arranged in line with, but spaced from the forward end of the slot in the body member and the first mentioned post co-acting with the walls of the slot in the body member to hold the arm in horizontal 25 position until the rear end of the slot in said arm has reached said second post, the arm when it has reached the last mentioned position being movable pivotally about the second post in an upward or downward slanting position.

8. An automobile signal according to claim 6 in which the arm is provided with a post for convenience in moving it relatively to the body member and said post is provided with a head which may be turned to 30 fix the arm in adjusted position.

9. An automobile signal according to claim 7 in which the first mentioned post is provided with a head for convenience in 35 moving the arm relatively to the body member and said head is mounted to be turned to fix the arm in adjusted position.

Signed at Shelbyville, in the county of 40 Shelby, and State of Kentucky, this 10 day of October, 1931.

JAMES ARCHIE BELL.
